UNITED STATES PATENT OFFICE

91,087

DESIGN FOR AN AUTOMOBILE

Anna R. Renner, New Canaan, Conn.

Application September 23, 1933. Serial No. 49,325

Term of patent 7 years

To all whom it may concern:

Be it known that I, ANNA R. RENNER, a citizen of the United States, residing at New Canaan, in the county of Fairfield and State of Connecticut, have invented a new, original, and ornamental Design for Automobiles, of which the following is a specification, reference being had to the accompanying drawing, forming part thereof.

Fig. 2 is a front perspective elevation thereof, and

Fig. 3 is a rear perspective elevation.

I claim:

The ornamental design for an automobile, as shown.

ANNA R. RENNER.
